UNITED STATES PATENT OFFICE.

FRED RICKS, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR SHAPING THE HEEL PORTIONS OF SHOE-UPPERS.

1,280,303.

Specification of Letters Patent.

Patented Oct. 1, 1918.

Application filed January 14, 1916. Serial No. 72,082.

To all whom it may concern:

Be it known that I, FRED RICKS, a subject of the King of England, residing at Leicester, Leicestershire, England, have invented 5 certain Improvements in Machines for Shaping the Heel Portions of Shoe-Uppers, of which the following description, in connection with the accompanying drawings, is a specification, like reference characters on the 10 drawings indicating like parts in the several figures.

This invention relates to machines for shaping the heel ends of boots and shoes. In machines for operating upon the heel 15 ends of completed uppers for shaping them under the influence of pressure or heat and pressure between an inside former, outside formers and flange-turning wiping means with a view to facilitating subsequent lasting or improving the work generally, it has been proposed to advance the formers to and 20 retract them from the wiping means after the completion of the flange turning operation.

25 Heretofore, as I am advised of the art, the inside former has been directly moved and the outside former has been mounted so as to permit it to be carried along with the inside former by force transmitted 30 through the work clamped between the formers. I believe it to be undesirable to rely upon the outside formers being advanced to or retracted from the flange-turning means merely as a result of the hold of 35 the formers upon the material of the upper.

An object of the present invention is therefore to improve upper molding, lasting and other upper shaping machines by providing means which not only permit the outside 40 formers to move with the inside former as it is advanced toward or retracted from the flange turning means, but to bring about this motion positively and independently of the work. This invention is herein shown for 45 illustrative purposes as applied to the upper molding machines which are shown and described in Brock United States Letters Patent Nos. 1,197,437 and 1,197,440, granted September 5, 1916, and which form an in- 50 turned sole attaching flange on the heel part of an upper, but it is to be understood that

the invention is likewise applicable to lasting machines, and also to molding machines which form an outturned sole attaching flange as shown for example in Brock 55 United States Letters Patent No. 1,160,185, granted Nov. 16, 1915. A feature of the present invention resides in the combination with inside and outside formers and flange forming wipers, of means for insuring the elevation of one of said formers when the other one is raised to compress the flange against the wipers. According to the illustrated embodiment of the invention the outside and inside formers are positively 60 moved together in the advance or retraction of the formers with relation to the wiping means after the wiping operation.

The motion of the outside forming means may advantageously be derived from the 70 moving inside former by appropriate mechanical connections between them. A convenient construction for securing this end is shown by way of example in the accompanying drawings in which parts of a machine of the kind described in the specification of Brock United States Letters Patent No. 1,197,437, granted Sept. 5, 1916, are illustrated.

Figure 1 of the drawings is a side elevation of so much of that machine with this 75 invention applied to it as is necessary for illustrating this invention.

Fig. 2 is a perspective view showing the 80 new features.

Fig. 3 is a plan view, partly in section, showing the connections of the formers to their operating elements.

The inside former 1 is mounted upon a 90 rod 2 adapted to be reciprocated in the post 3 by suitable mechanism. Attached to the rod 2 and projecting through an opening in the post 3 is a yoke 4 bearing two rods 5 and 5'. These rods are rigidly connected to members 6 (one only of which is shown) 95 having flanges entering slots in the outside formers 7 and 7'. The outside formers are pivoted on pins 8 and 8' so as to be free to rise somewhat in slots, of which one is shown at 9. These slots are formed in the operating elements 10 which slide on the frame 11 for closing together the outside formers. 100

The flanges of the members 6 may be of such width and the slots in the outside formers of such depth as to allow sufficient margin of overlap between the flanges and slot walls 5 to maintain the flanges of members 6 in overlapping lifting relation to the outside formers in the closed position of said formers relatively to inside formers varying somewhat in transverse dimensions.

10 In operation a completed upper is passed over the former 1 as usual and drafted forwardly about the same. Then the machine is treadled and the former is drawn into the machine by connection from bar 15 with 15 the power mechanism, not shown. When the former with the upper surrounding it has become seated backwardly against the outside formers the latter are closed around the inside former by connection from rod 20 16 to the power mechanism and thereafter the wipers 18 are advanced and closed by rod 20 over the tread face of former 1 to shape the heel seat flange. Next it is necessary to crush down the flange and compress 25 it between the wipers and former 1 and for this purpose the former carrying rod 2, which is now over a plunger connected with toggle 25, is elevated by straightening of the toggle through its connection with the power 30 mechanism. In such elevation of rod 2 and the inside former 1, the outside formers are compelled to participate fully and unvaryingly by reason of the motion of yoke 4, rods 5, 5' and members 6. The loose connections of the outside formers with their 35 operating members 10 permit them to rise without disturbing the operating mechanism. On the completion of the molding operation, the rod 2 retires and the reverse operations 40 take place.

By operating in such a way the compression of the flange after the wiping operation can be secured without straining the upper in such a way as to result in damage thereto. This invention is also applicable to heel 45 lasting machines, in the use of which it is customary to force the last upwardly against the wipers to crush the flange down upon the innersole and it is desirable that the 50 heel band, which corresponds to outside formers, shall be elevated with the last.

Having explained the nature of this invention and described an illustrative construction embodying the same, I claim as new and 55 desire to secure by Letters Patent of the United States:—

1. In a machine for molding the heel ends of uppers for the purpose indicated, the combination with operating mechanism, of 60 inside and outside formers and heel flange forming wipers arranged to permit the formers to be raised to compress the flange against the wipers, and means insuring the elevation of both the inside and outside 65 formers together.

2. In a machine for molding the heel ends of uppers for the purpose indicated, the combination with operating mechanism, of an inside former, outside formers and heel flange forming wipers arranged to permit the formers to be raised to compress the flange against the wipers, elevating means operating upon the inside former, and connections from said means to the outside formers arranged to cause the outside formers to move to the same extent as the inside former. 70

3. In a machine for molding the heel ends of uppers for the purpose indicated, the combination with operating mechanism, of an inside former, outside formers movable relatively to each other, and heel flange forming wipers arranged to permit the formers to be raised to compress the flange against the wipers, means for elevating the inside former and connections from said means to the outside formers for producing similar elevation of the latter, said connections including devices having horizontally sliding engagement with the outside formers to 85 permit the operative movements of the outside formers relatively to each other. 90

4. In a machine for molding the heel ends of uppers for the purpose indicated, the combination with operating mechanism, of an inside former, two outside formers and heel flange forming wipers arranged to permit the formers to be raised to compress the flange against the wipers, a support for the inside former and unyielding connections from said support to both outside formers arranged for operation in any operative position of said outside formers to move the outside formers both upwardly and downwardly with the inside former. 95

5. In a machine for molding the heel ends of uppers, the combination with an inside mold, a plunger by which the mold is moved vertically, lateral extensions from the plunger, vertical rods on said extensions, outside 110 formers movable to close and open relatively to the inside mold, and connections between said outside formers and the heads of the rods for compelling the outside formers to partake of a vertical movement of the inside mold. 115

6. In a machine for molding the ends of uppers for the purpose indicated, the combination with an inside mold, outside formers movable to close and open relatively to the inside mold, end flange forming wipers arranged to permit said mold and formers to be moved to compress the flange against the wipers, a support for the inside mold movable in the flange compressing direction, and rigid connections between said support and the outside formers insuring movement of the outside formers with the inside mold in the flange compressing direction. 120

7. In a machine for forming the ends of 130

shoe uppers, a shoe form to which the shoe upper is to be molded, upper molding formers coöperating with one end of said shoe form and movable to close and open relatively to said end of the shoe form, wipers for flanging the edge of the upper materials projecting beyond the edge of said form, and mechanism for moving said shoe

form and said molding formers positively and in unison in a direction to compress 10 the flanged edge of the upper against said wipers.

In testimony whereof I have signed my name to this specification.

FRED RICKS.
